KEY COUPLING DEVICE

Robert L. Muller, Detroit, Mich., assignor to
 Burroughs Adding Machine Company, Detroit,
 Mich., a corporation of Michigan

Application October 20, 1941, Serial No. 415,733

7 Claims. (Cl. 235—145)

This invention relates to business machines of the full keyboard type, that is, machines with a plurality of rows or banks of keys and in which a key in each of a plurality of rows can be depressed simultaneously to set up an entry to be made by the machine.

An object of the invention is to provide, in such a machine, improved means to so cooperate with the keys of selected groups of keys that when any key in any such group is depressed, the remaining keys of the same group are also depressed.

A further object of the invention is to provide an improved means of the character stated which can be incorporated in a machine of the character specified flexibly to permit of wide choice in grouping of keys.

A further object is to provide an improved means of the character stated which can not only be incorporated in machines being built but also be applied to machines of the character specified at any time after manufacture with a minimum of alteration in the existing machine structure and maximum facility.

A further object is to provide an improved means of the character stated which will permit of easily re-grouping the keys when desired.

A further object is to provide an improved means of the character stated which will minimize the amount of care required from the operator in depressing grouped keys.

A further object of the invention is to provide an improved means of the character stated which is inexpensive and easy to manufacture and apply to the machine and is also reliable in use.

Further objects of the invention will be pointed out in the following description of preferred embodiments of the invention shown in the accompanying drawings, in which:

Figure 1 is a vertical section through a machine equipped with the invention showing particularly the parts more closely associated with the invention, other parts being omitted for the sake of clearness;

Fig. 2 is a plan view of a portion of keyboard of the machine shown in Fig. 1;

Fig. 3 is a rear elevation of portions of the printing type bars of the machine in Fig. 1;

Fig. 4 is a perspective view of a portion of the keyboard, parts being broken away to show more clearly one form of bail associated with a group of keys to be depressed together as a group and the manner of cooperation of said bail with the keys;

Fig. 5 is a vertical section through a portion

of a keyboard having key-group bails of the form illustrated in Fig. 4;

Fig. 6 is a perspective view of a portion of a keyboard equipped with a modified form of key-group bail, portions being broken away to reveal more clearly the form of construction of the bail and the manner of cooperation of the bail with the keys;

Fig. 7 is a vertical section of a portion of another style of machine equipped with the invention; and

Fig. 8 is a perspective view of another modified form of key-group bail and of the keys cooperating therewith.

15 In Fig. 1 the invention is shown as applied to a well-known Burroughs "high keyboard" type of machine, the general construction of which is well known and illustrated and described in many patents. The machine is a full keyboard type of 20 calculating machine, that is, a calculating machine having a plurality of forwardly and rearwardly extending banks or rows of keys 20, one bank of which is shown in Fig. 1.

The stem of each key 20 passes through vertically aligned apertures in top and bottom plates 21 and 22 of the keyboard and the lower end of the stem of each key cooperates with the forward arm of a detent bell crank 23. The lower arm of each detent bell crank of each bank of keys 30 extends through a corresponding slot 24 in a key latch slide 25 extending forwardly and rearwardly along the entire bank of keys. When any key is depressed, its detent bell crank 23 is rocked clockwise, as viewed in Fig. 1, and its downward arm shifts the latch slide 25 rearwardly until the rearward edge of an aperture 26 in the rear end of the slide 25 is rearward of a shoulder on the lower edge of one arm of a latch yoke 27 for the key-bank, which is thereupon rocked counterclockwise by its spring 28, about the rod 29 on which it is pivoted, to latch the slide 25 in its rearward position. In the rearward movement of the slide 25 the edges of the slide at the forward ends of the slots 24 move beneath shoulders on the downward arms of the detent bell cranks 23 of all undepressed keys, thereby latching all undepressed keys against depression. The detent bell crank 23 for the depressed key is held in rocked position by the edge of the slide 50 25 at the forward end of the corresponding slot 24 being positioned above the shoulder projection on the lower arm of the bell crank.

For each detent bell crank 23 in a bank there is a stop wire 30, the rear upper end of which is 55 hooked through an aperture in the end of the

lower arm of the detent bell crank below the latch slide 25 and the forward hooked end of which is guided in a respective one of a series of spaced slots 31 in each of a pair of comb plates 32 for the key-bank. The depression of any key except the rearmost key in a key-bank, therefore, pulls a corresponding stop wire 30 rearwardly to place the transverse portion of its forward hooked end between the pair of comb plates 32 in the path of a shoulder 35 of an actuator sector 36 between the comb plates 32 and carried by the forward arm of a lever 37 pivoted on a shaft 38 running transversely through the machine. The levers 37 for the several banks of the machine are urged clockwise in Fig. 1 by springs 39 but normally held in their normal positions of Fig. 1 by a bail 40.

Rearward movement of the key latch slide 25 by depression of key also causes an up-bent lug 41 on the forward end of the slide to engage a projection on a zero-stop latch 42 pivoted on a rod 43 and rock said zero-stop latch clockwise against the tension of a spring 44 to remove a lateral lug 45 on the zero-stop latch rearwardly from beneath a shoulder 46 on the actuator sector 36 so that when, during a cycle of operation of the machine, the bail 40 is swung clockwise in Fig. 1 in a well-known manner, the levers 37 and actuator sectors 36 for the key banks in which keys have been depressed are moved clockwise by their springs 39 until the shoulders 35 on such actuator sectors engage the hooked forward ends of the stop wires 30 for the depressed keys.

On the rearward end of the rear arm of each of the levers 37 is a type carrier supporting a series of type members 50 with appropriate character type formed on their rearward end faces. During the machine cycle, when the bail 40 has completed its clockwise movement and the sector 36 and lever 37 for each bank of keys in which a key has been depressed have moved clockwise to the position determined by the stop wire 30 for the depressed key, the type members 50 which have been positioned along the printing line of a platen 51 are driven against a work sheet or record strip, held around the platen, by printing hammers 52 which are then fired against the forward ends of the shanks of the type members 50 which extend forwardly through the type carriers. The printing mechanism is basically of the type disclosed in the Burroughs Patent 505,078 and the construction and operation thereof need not be further described in detail herein.

After the printing hammers 52 have been fired to effect the printing impression, the bail 40 is returned counterclockwise during the return stroke of the machine cycle to its normal position of Fig. 1 and thereby returns the levers 37 and sectors 36 to their Fig. 1 positions.

During the return stroke of the machine cycle, a bail 55, carried by a pair of arms 56 pivoted at 57 on the side plates of the machine frame, is rocked forwardly of its Fig. 1 position to engage and lift the tails of the latch yokes 21, thereby releasing the slides 25 and zero-stop latches 42 for return to their normal positions of Fig. 1 by the springs 44. The return of the latch slides 25 to their normal forward positions unlatches all of the keys in their respective banks and permits the detents 23 for the depressed keys to be returned counterclockwise to their normal positions by springs 60 connected at their upper ends to lugs on spacing plates 61, located between the plates 21 and 22 between the key-banks, and at their lower ends to studs 62 secured in the detents 23.

and extending laterally through slots in the spacing plates 61.

A plurality of key-banks at the right-hand side of the keyboard, viewing the machine from the front, will generally be employed for controlling the printing and registering of amounts, and the actuator sectors 36 for those banks of keys co-operate with a suitable registering mechanism 65 (Fig. 1) of a character appropriate to the calculating work to be performed upon the machine. Meditately or immediately to the left of the amount section of the keyboard are a plurality of banks 70 of keys for controlling the printing of desired data, such as designations of goods or services, or other characteristics of the items to which the amounts entered in the amount section of the keyboard relate.

The designations to be printed under the control of the keys in the key-banks 70 comprise varying numbers of characters necessary to adequately identify or classify the various items. Fig. 2 illustrates a portion of the keyboard of a machine equipped with the invention and suited for use in connection with an automobile service business wherein it is desired that the business records to be kept and/or the statements of account to be given to the customers should list opposite the amounts of the debit and credit entries the nature of the goods, services, or the like, in respect of which such amounts are charged or credited to the accounts. In the example illustrated in Fig. 2, it will be seen that certain designations such as "Oil," "Wash," "Tires" and "Parts" require the use of only two banks of keys and two printing type carriers for the printing thereof, whereas other designations shown on the keyboard of Fig. 2 require the use of three, four or six banks to take care of the printing of the necessary characters.

Fig. 3 illustrates the arrangement on the type carriers of the type for the characters involved in the designations shown in Fig. 2, there being generally two character types on each type member 50 except in the highest order type carrier at the right, viewing the machine from the rear as in Fig. 3 (or at the left, viewing the machine from the front as in Fig. 2), where it may be necessary, in some instances, as in the case of the designation "Tires," to employ wider type carries 50X with three letter types and extending laterally partially behind the next higher order type carrier which, in such case, would not be provided with types. Likewise, the keys for the corresponding higher order would be omitted from the keyboard and the key slots either omitted or closed by suitable means such as plugs 72.

If the letters corresponding to those on the various type members 50 were placed directly on the tops of the corresponding keys in the banks 70, the printing of the required designations could be effected by the operator depressing individually each of the keys bearing the required characters. However, that would greatly slow up the work performed on the machine, particularly in the case of long designations such as "Gasoline" or "Returned Mdse.", to permit the depression of all of the keys required for the printing of a given designation by a single finger pressure. The type members 50 bearing the required character type are so arranged in the respective carriers on the rear arms of the levers 37 that all of the designation keys required to be depressed for each designation are arranged in the same horizontal row of keys in adjacent banks of designation keys and the tops of all of the designation

keys required to be depressed for the printing of each individual designation are embraced in a single auxiliary key top or bridge 75, as illustrated in Figs. 4 and 5.

The bridge 75 is formed of a preferably sheet metal channel member having a substantially flat top portion 76 with side flanges 77 turning inwardly under the upper end portion of the key top and downwardly turned rounded end flanges 78 (Fig. 5) fitting closely the edge surfaces of the end keys of the group of keys allotted to the designation displayed on the upper surface of the bridge. One of the side flanges is notched as at 77a to permit of easy insertion of the keys in the bridge member by placing an edge of the key top in the angle between the top portion 76 and the other flange 77 opposite the notch 77a, then tilting the key top into contact with the underside of the top portion 76 of the bridge member and finally sliding the key top lengthwise of the bridge member to the proper position therein. Between the under surface of the flat top portion 76 of the bridge and the upper faces of the keys embraced thereby, a strip 79 of somewhat resilient material, such as felt, may be inserted, for a purpose to be mentioned later.

The bridges 75 might be sufficient to enable the operator to depress the entire group of keys allotted to each designation by a single finger depression if the operator's finger were, in each instance, always pressed at or near the mid portion of the bridge embracing the group of keys. However, in their efforts to speed up work, operators frequently will exert finger pressure against the bridge 75 at or near one or the other of the ends thereof, and in the case of the longer bridges for the longer designations, the pressure exerted at or near one end of the bridge may not always result in full depression of one or more of the keys at the opposite end of the group, so that the required designation is not completely printed. To avoid such misoperations, the invention provides a means to insure that the entire group of keys allotted to each designation will be fully depressed as a group when any key of the group is depressed.

As shown in Figs. 4 and 5, a bail 80 adapted to be inserted between the upper and lower plates 21 and 22 of the keyboard has slots 81 to receive the stems of the keys of the group connected by the bridge 75 and, forwardly of each of said slots and key stems, has a downwardly turned lug 82 to bear against the lower plate 22 of the keyboard. The edge of the bail member 80 at the rear end of each of the slots 81 is held seated in a notch 83 in the stem of the key passing through said slot by means of a retaining rod 84 inserted between the downturned lugs 82 and the forward edges of the respective key of the group. Thus, irrespective of the bridge 75 connecting the tops of the keys of the group allotted to a particular designation, depression of any one of the keys in the group will depress the rearward portion of the bail 80, causing the bail to rock about its contacts between the lugs 82 and the lower keyboard plate 22, from the position of the left-hand bail member 80 of Fig. 5 to the position of the right-hand bail member 80 of that figure, whereby all of the keys of the group cooperating with the bail member 80 are depressed by the depression of any one or more of the keys of the group. Those portions of the bail at which the downwardly bent lugs join with the remainder of the bail member are spaced from the upper plate 21 of the keyboard, when the ends of the lugs rest on the

lower plate 22, preferably only sufficiently to give proper clearance between the said bail member and the upper keyboard plate 21 as the bail rocks from the position of the left-hand bail member of Fig. 5 to the position of the right-hand bail member of that figure, and back again, so that if, in the group of keys associated with the bail, any key not immediately under the operator's finger offers any greater than normal resistance against depression when the operator attempts to press the group of keys, any possible twisting of the main upper portion of the bail will result in that portion of the bail 80 where the lug 82 for the corresponding key joins the remainder thereof of contacting against the upper keyboard plate 21 and so enabling the bail either to overcome the resistance against depression of the key or to block the depression of any of the keys of the group. The notches 83 are of less vertical width at their outer open ends than at their closed inner ends to minimize looseness between the key stems and the coupling bail 80 without interfering with the rocking of the bail during depression and restoration of the keys.

As the bail 80 itself is adequate to depress all of the keys of the group with which it cooperates upon depression of any of those keys, it is not necessary for the keys to be rigidly secured in the corresponding bridge member 75. The insert 79, while preventing looseness of the key tops in the bridge member, permits of slight movement of the keys relative to the bridge member sufficient to prevent binding of the parts as the keys are depressed and restored and so aids in securing smooth and easy operation.

The bail members 80 are made of various lengths suited for coupling either two or any greater number of keys which might be required for any designation to be printed by a machine of the character stated and are not only easily installed at the time of original assembly of such a machine but may be inserted and removed or exchanged easily at any time in a previously constructed machine. The keys employed are the same as standard keys for the machine to which the invention is applied except only for the notch 83 in the rearward end of the stem of each key.

In assembling the parts the number of keys required for the desired designation to be printed are assembled in a bridge member 75 of a length appropriate to the number of keys to be assembled therein, the tops of each of the keys in turn being slipped into the channel in the bridge member 75 at the notch 77a and slid lengthwise to its proper position in the bridge member. A bail member 80 of appropriate length and with the appropriate number of slots 81 for the number of keys inserted in the bridge member 75 is then placed against the under surface of the number plate 21 of the keyboard with its slots 81 in registry with the slots in the plate 21. Then the stems of the keys secured in the bridge 75 are passed through their respective slots in the keyboard plate 21 and through the registering slots in the member 80 until the notches 83 in the key stems are beneath the keyboard plate 21, whereupon the bail member 80 is drawn forwardly into the notches 83 and the retaining rod 84 is slid lengthwise between the lugs 82 and the forward edges of the key stems, the ends of the rod 84 being then bent over to retain the rod against unintentional movement longitudinally out of retaining position. The parts may be disassembled at any time by simply straightening out one end of the rod 84 and pulling the rod lengthwise in the

direction of its other end to remove it from retaining position, after which the bail may be moved rearwardly to free it from the notches 83 in the stems of the keys, which may then be removed from the keyboard. By also suitably positioning the appropriately selected type in the type carriers, the machine may be adapted for the printing of any desired selection of designations and the selection of designations may be altered in any desired manner at any time to suit the requirements of the work to be done on the machine.

Fig. 6 illustrates a modified form of construction in which the bail member 80a, instead of having slots through which the stems of the designation keys pass, has rearwardly extending lugs 90 each adapted to engage the side edge of the stem of a designation key in a notch between lugs or shoulders 91 thereon, the key stems being arranged in the keyboard with their flat faces facing forwardly and rearwardly, instead of laterally as in Figs. 4 and 5. Each of the lugs 90 is also formed with a notch between shoulders 92 thereon to receive the lateral edge of the key stem and prevent the bail member 80a from being displaced forwardly or rearwardly out of operative relation to the key stems. The bail 80a is held against movement laterally of the keyboard, that is, longitudinally of the bail member, out of operative relation to the key stems by means of a retaining stud or screw 93 extending between and secured in the upper and lower keyboard plates 21 and 22, said stud 93 being inserted and secured in position after the bail member 80a has been inserted and placed in operative position in relation to the keys. The bail member 88 can be removed at any time when it is desired to change the designation set-up by merely removing the screw or stud 93 and moving the bail member a short distance laterally and then forwardly, after which it may be removed laterally from the keyboard.

Fig. 8 shows another modified form of construction in which the slots 81b on the bail member 80b for all of the keys of the group excepting the leftmost key of the group are substantially wider than the thickness of the key stems, the left-hand portions of the slots 81b being of sufficient length to pass the entire lower portion of the key stem therethrough, whereas the right-hand portion of each of said slots is shorter by nearly the depth of the notch 83b. After the stems of the keys secured in the bridge member 75 are passed through the openings in the upper keyboard plate and through the registering longer left-hand portions of the slots 81b until the notches 83b in the key stems are in alignment with the edges of the bail member 80b at the rear ends of the slots 81b and the bail member 80b is then pulled forwardly and slid a short distance to the left relative to the keys, the shortness of the right-hand portions of each of said wide slots 81b will cause the rear edge of the bail 80b at the rear end of the slots to be retained in the notches 83b in the key stems. Instead of being formed with another slot like the wide slots 81b for the leftmost key of the group of keys to be connected, the left-hand edge of the top portion of the bail member 80b may simply be formed with a notch to receive the portion of the stem of said leftmost key at the level of the notch 83b therein when the bail member 80b is moved leftward into operative position, as just mentioned. To hold the bail member 80b against unintentional movement toward the right, the lug 82b in 75

front of the leftmost key of the group is formed with a projection 95 which, after the bail member 80b has been moved leftward into operative position relative to the keys, may be bent down on the left-hand side of the stem of the leftmost key of the group to prevent movement of the bail member 80b to the right. The bail member 80b may be removed by simply bending the lug 95 out of the way and performing the assembling steps in reversed order.

Fig. 7 illustrates the application of the invention to a machine such as the well-known Burroughs "Class 4 Visible" machine having a keyboard which, like that of the Gooch Patent 1,395,044, has only the upper one, 21, of the two keyboard plates 21 and 22 of Figs. 4 to 6. To provide bearing for the lower ends of the lugs 82c of the bail members 80c, strips, bars or plates 97 are mounted in position at the appropriate distance below the keyboard plate 21 by means of studs 96 which, if a bail member of a form similar to the bail member 80a of Fig. 6 is employed, may also serve to retain the bail member against displacement laterally of the keyboard out of operative relation to the keys.

Most calculating machines are provided with an error key which, when depressed, will release the keys in all or most of the key-banks of the machine and permit them to be restored by their springs. Some machines are provided alternatively or, as the Burroughs "high keyboard" machine of Fig. 1, additionally in each key-bank with individual release keys or buttons which may be depressed to release only the depressed key in the individual key-bank with which the release key or button is associated. Such a single bank release key or button is shown in Fig. 1 at 100. Normally, the stem of the release key or button 100 would, upon depression, engage directly a rearwardly extending lug 101 of a yoke member 102 pivoted on the rod 103. The yoke 102 has a downwardly extending arm engaging against a lateral lug on an upwardly extending arm of the latch yoke 27, whereby the yoke 102 is normally held in the position of Fig. 1 but, upon depression of the release key or button 100, rocks the latch yoke 27 clockwise against the tension of its spring 28 to release the key latch slide 25 for the corresponding key bank. When the designation keys in the key-banks 70 are coupled in designation groups by the bridges 75 and bail 80, a depressed group of designation keys could be released only by simultaneous depression of all of the release keys or buttons 100 in all of the key-banks containing one of the keys of the depressed group, inasmuch as all of the keys of the depressed group would be held in depressed position by the bail 80 while any one of the keys of the group remained latched in depressed position. However, a bail having side arms 104 pivoted on the rod 102 has its transverse connecting portion 105 overlying the rearward arms 101 of all of the release yokes 102 of all of the designation key-banks 70 and positioned under the stems of all of the release keys or buttons 100 of all of said designation key-banks 70. Depression of any one of the release keys or buttons 100 for any one of the designation key-banks 70 will cause the bail 104, 105 to rock all of the release yokes 102 to release all of the latches 27 of all of the designation key-banks 70 to release any depressed designation key-group and permit restoration thereof. It is obvious that the provision of the bail 104, 105 will permit the omission of all but a single one of the release keys or buttons for the designation

key-banks 70, although it is found most convenient for manufacturing as well as other purposes to adhere to standard construction and provide the usual release key 100 for each individual key-bank, even though the invention is being applied to the machine at the time of its original manufacture.

I claim:

1. In a machine of the class specified having a keyboard comprising upper and lower plates, the combination of a row of at least two simultaneously depressible keys each having a key-stem extending through said plates, a coupling member extending the length of said row of keys between said plates, said coupling member having slots through which the stems of said keys extend and each of said key-stems having in one edge between said plates a notch receiving a portion of said coupling member adjacent the slot therein through which said key-stem extends, said coupling member having portions to bear on at least one of said plates to support said coupling member for rocking movement thereon along a line substantially removed from said portions in said key-stem notches, and means to retain said portions of said coupling member in said notches.

2. In a machine of the class specified having a keyboard comprising upper and lower plates, the combination of a row of at least two simultaneously depressible keys each having a key-stem extending through said plates, a pair of opposed shoulders on each key-stem between said plates, a supporting means, a coupling device comprising a plate extending the length of said row of keys between said keyboard plates and having slots through which the stems of said keys extend and having a portion adjacent an edge of each slot engaging between said shoulders on the key-stem extending through said slot, said coupling device also comprising portions extending from said plate to bear rockably on one of said keyboard plates on a line substantially removed from said key-stem shoulders, and means to retain said portions of said coupling member engaged between said shoulders.

3. In a machine of the class specified, the combination of a row of at least two simultaneously depressible keys each having a key-stem, a pair of opposed shoulders on each key-stem, a supporting means, and a coupling device comprising a plate extending the length of said row of keys and having slots through which the stems of said keys extend, having a portion adjacent an edge of each slot engaging between said shoulders on the key-stem extending through said slot, and having portions at the opposite edges of a plurality of said slots to retain said first-named portions engaged between said shoulders, said coupling device also comprising portions extending from said plate to bear rockably on said supporting means on a line substantially removed from said key-stem shoulders.

4. In a machine of the class specified, the combination of a row of at least two simultaneously depressible keys each having a key-stem, a pair of opposed shoulders on each key-stem, a supporting means, and a coupling device comprising a plate extending the length of said row of keys

and having slots through which the stems of said keys extend, having a portion adjacent an edge of each slot engaging between said shoulders on the key-stem extending through said slot, and 5 having portions at the opposite edges of a plurality of said slots to retain said first-named portions engaged between said shoulders, said coupling device also comprising members extending from said plate to bear rockably on said supporting means on a line substantially removed from said key-stem shoulders, and means on at least one of said members to retain said last-mentioned portions of said plate in effective relation with said key-stems.

10 5. In a machine of the class specified, having a keyboard comprising upper and lower keyboard plates, the combination of a group of simultaneously depressible keys having key-stems passing through said plates, coupling elements on each of said key-stems between said plates, a coupling member positioned between said keyboard plates and having portions to bear against at least one of said plates and coupling portions substantially spaced from said bearing portions and coupled with the coupling elements on each of said key-stems to cause rocking of said coupling member and full depression of all of said keys upon full depression of any of said keys, and displaceable means to maintain the coupling portions of said coupling member in coupled relation with the coupling elements of said key-stems.

15 6. In a machine of the class specified, having a keyboard comprising upper and lower keyboard plates, the combination of a group of simultaneously depressible keys having key-stems passing through said plates, coupling elements on each of said key-stems, and a coupling member positioned between said plates and having portions to bear against at least one of said plates and extending into proximity to the other of said plates and portions spaced from said bearing portions and coupled with the coupling elements on each of said key-stems, and means to limit movement of said coupling member transversely of said key-stems whereby to maintain said coupling member coupled with said coupling elements on said key-stems and, in combination with said plates, to confine movement of said coupling member effected by depression of any of said keys substantially to rocking movement to cause simultaneous depression of the remainder of said keys.

20 7. In a machine of the class specified having a keyboard comprising upper and lower plates, the combination of a row of at least two simultaneously depressible keys each having a key-stem extending through said plates, a pair of opposed shoulders on each key-stem between said plates, a coupling device comprising a plate extending the length of said row of keys between said plates and having portions engaging between said shoulders on each of said key-stems and portions extending from said latter plate to bear rockably on one of said keyboard plates on a line substantially removed from said key-stem shoulders, and means to retain said portions of said coupling member engaged between said shoulders.

ROBERT L. MULLER.
